William F. Halstrick

By Ralph Koenig ATTORNEY.

UNITED STATES PATENT OFFICE.

WILLIAM F. HALSTRICK, OF CHICAGO, ILLINOIS, ASSIGNOR TO NATHAN STEINER, OF ST. LOUIS, MISSOURI.

DESIGN FOR A GRILLE OR PANEL FOR A PHONOGRAPH-CABINET OR SIMILAR ARTICLE.

54,083.

Specification for Design.

Patented Nov. 4, 1919.

Application filed June 9, 1919. Serial No. 302,986. Term of patent 3½ years.

To all whom it may concern:

Be it known that I, WILLIAM F. HALSTRICK, a citizen of the United States, residing at the city of Chicago, county of Cook, State of Illinois, have invented a certain new, original, and ornamental Design for a Grille or Panel for a Phonograph-Cabinet or Similar Article, of which the following is a specification, reference being had to the accompanying drawing, forming a part thereof.

The drawing is an elevational view of a grille or panel for a phonograph cabinet or similar article, showing my new design.

I claim:

The ornamental design for a grille or panel for a phonograph cabinet or similar article, substantially as shown.

WILLIAM F. HALSTRICK.
